(57) CLAIM

The ornamental design for equipment for distribution or control of electric power, as shown and described.

DESCRIPTION

FIG. 1 illustrates a front side perspective view of a first embodiment of equipment for distribution or control of electric power.

FIG. 2 illustrates a front side view of the equipment shown in FIG. 1.

FIG. 3 illustrates a right side view of the equipment shown in FIG. 1.

FIG. 4 illustrates a left side view of the equipment shown in FIG. 1.

FIG. 5 illustrates a rear side view of the equipment shown in FIG. 1.

FIG. 6 illustrates a top side view of the equipment shown in FIG. 1.

FIG. 7 illustrates a bottom side view of the equipment shown in FIG. 1.

FIG. 8 illustrates a front side perspective view of a second embodiment of equipment for distribution or control of electric power.

FIG. 9 illustrates a front side view of the equipment shown in FIG. 8.

FIG. 10 illustrates a right side view of the equipment shown in FIG. 8.

FIG. 11 illustrates a left side view of the equipment shown in FIG. 8.

FIG. 12 illustrates a rear side view of the equipment shown in FIG. 8.

FIG. 13 illustrates a top side view of the equipment shown in FIG. 8.

FIG. 14 illustrates a bottom side view of the equipment shown in FIG. 8.

FIG. 15 illustrates a front side perspective view of a third embodiment of equipment for distribution or control of electric power.

FIG. 16 illustrates a front side view of the equipment shown in FIG. 15.

FIG. 17 illustrates a right side view of the equipment shown in FIG. 15.

FIG. 18 illustrates a left side view of the equipment shown in FIG. 15.

FIG. 19 illustrates a rear side view of the equipment shown in FIG. 15.

(Continued)

FIG. 20 illustrates a top side view of the equipment shown in FIG. 15.

FIG. 21 illustrates a bottom side view of the equipment shown in FIG. 15.

FIG. 22 illustrates a front side perspective view of a fourth embodiment of equipment for distribution or control of electric power.

FIG. 23 illustrates a front side view of the equipment shown in FIG. 22.

FIG. 24 illustrates a right side view of the equipment shown in FIG. 22.

FIG. 25 illustrates a left side view of the equipment shown in FIG. 22.

FIG. 26 illustrates a rear side view of the equipment shown in FIG. 22.

FIG. 27 illustrates a top side view of the equipment shown in FIG. 22; and,

FIG. 28 illustrates a bottom side view of the equipment shown in FIG. 22.

The broken lines shown in the figures are for the purpose of illustrating portions of the equipment that forms no part of the claimed design.
